UNITED STATES PATENT OFFICE.

JEREMIAH REAVS WHITE, OF RAYMOND, MISSISSIPPI.

PLOW.

SPECIFICATION forming part of Letters Patent No. 395,861, dated January 8, 1889.

Application filed June 11, 1887. Serial No. 241,060. (No model.)

To all whom it may concern:

Be it known that I, JEREMIAH REAVS WHITE, of Raymond, in the county of Hinds and State of Mississippi, have invented a new and useful Improvement in Plows, of which the following is a specification.

My invention is an improvement in plows; and it consists in certain novel constructions of the scraper-blade, its supporting-standard, and the fastening devices, as will be herein-after fully described, and pointed out in the claims.

In the drawings, Figure 1 is a side elevation of a plow provided with my improvements. Fig. 2 is a side elevation, and Fig. 3 a rear elevation, of the improvements. Fig. 4 is a detail view of the clip. Fig. 5 is an edge view of the scraper-blade. Fig. 6 is a sectional elevation showing a different form 20 of fastening from that shown in Fig. 3. Fig. 7 is a detail rear view of the blade shown in Fig. 6; and Figs. 8, 9, and 10 are detail face views of shovel-blades constructed according to my invention.

25 In practice the standard A is lapped alongside of beam B, and is secured thereto by clip C. This clip is formed of L-shaped sections c c and nuts c' c', as shown most clearly in Fig. 4, the side bars, 1, of sections c being flat, so as to clamp the standard A firmly and to prevent any slipping thereof. These side bars, 1, are slotted to permit the adjustment 30 of the clip to different sizes. The clip being thus adjustable or extensible both laterally and vertically, it can be fitted to beams narrow in one direction and wide in the other, or to those narrow or wide in both directions, as will be readily understood from Fig. 4. At its lower end the standard has a curved seat 35 at 2 for the blade D, and is twisted at 3 at a point just above said blade, the curve or twist of said standard being such that the face 4 of the standard above the twist or bend shall be about or approximately in line with the 40 lower rear corner of the blade. This is most clearly shown in Fig. 3 of the drawings.

To permit the securing of the blade to the standard, I provide it with one and sometimes two or three bolt-holes, d, as will be understood from Figs. 8, 9, and 10. By the use 45 of the two and three holes the blade may be

thrown farther forward as it is worn to bring its scraping-edge into position to cut more or less, as may be desired. The securing-bolt E is passed through the opening d, and thence 5 through an opening, F, in the standard, and is secured by a nut, e. It is usual to provide the standard with a bolt-hole, f, for the set-screw G, which may be preferred for use to more tightly secure the blade in any of its 6c adjustments on the bolt E. When this screw G is employed, indentations, as g, may be employed; or the gashes or grooves h, as shown in Fig. 3, may be provided to receive the point of the screw. However, it may be 65 regarded as preferable to provide the gashes h and to form the standards or uprights with an oblong end projection or tooth, H, to enter the same, and thus serve to secure the blade firmly in position. 70

It will be noticed that the points of the blade at 4 4 are rounded or sloped to keep it from bending or breaking. The curve of the blade is cylindrical, so that all of its corners lie in a common plane, so that the opposite 75 edges will cut alike when the blade is reversed.

By bringing the lower corner of the blade in line with the standard the whole scraper is thrown to the left of the plow-point, and 80 consequently trims off the row between the bar of the plow and the plants.

What I claim is—

1. The scraper-blade as described, in combination with the standard twisted at a point 85 just above the blade, the curve or twist of said standard being such that the face of the standard above the bend and the lower rear corner of the scraper-blade shall be approximately in line, and fastenings for securing 90 the scraper-blade to the standard, substantially as set forth.

2. A reversible scraper-blade made of oblong diamond form and cylindrical in curve, so that all the corners will touch a flat surface, and having a central bolt-hole and indentations or gashes on either side of the center, substantially as set forth. 95

JEREMIAH REAVS WHITE.
